UNITED STATES PATENT OFFICE.

ROBERT REA, OF PORTLAND, OREGON, ASSIGNOR TO PACIFIC EVAPORATOR COMPANY, OF PORTLAND, OREGON, A CORPORATION OF OREGON.

METHOD OF DRYING MATERIALS AND DRIER THEREFOR.

1,320,569.

Specification of Letters Patent.

Patented Nov. 4, 1919.

Application filed May 16, 1916. Serial No. 97,824.

To all whom it may concern:

Be it known that I, ROBERT REA, a citizen of the United States, residing at Portland, in the county of Multnomah and State of Oregon, have invented new and useful Improvements in Methods of Drying Materials and Driers Therefor, of which the following is a specification.

This invention relates to a method of drying material and driers therefor and consists in certain improvements therein as will be hereinafter fully described and pointed out in the claims.

More particularly the invention relates to driers especially designed for drying fruit. In this way it is desirable to have all parts subjected to the drying process so that the fruit may be thoroughly dried and thus prevent deterioration and it is also desirable that the fruit be uniformly dried.

The invention is illustrated in the accompanying drawings as follows:

Figure 1 shows a horizontal section of the drier on the line 1—1 in Fig. 2.

Fig. 2 a section on the line 2—2 in Fig. 1.

Fig. 3 a side elevation of one of the exhaust channels.

Fig. 4 a side elevation of the drier, partly in vertical section on the line 4—4 in Fig. 1.

1 marks the drier house as a whole. This has the drying chamber 2, the air lock 3 at one end of the drying chamber and the air lock 4 at the opposite end of the drying chamber. A heating chamber 5 is arranged

35 at one side of the drying chamber 2 and this has a series of steam coils 5^a arranged at various levels. Steam is delivered to these coils through the pipe 5^b, the steam being controlled in the various coils by valves 5.

40 These coils are so adjusted as to give uniform heat to different parts of the drier so that all parts of the fruit from top and bottom are uniformly dried. The passage of air through the coils is controlled by the doors or valves

45 6 and 7.

Air is exhausted through the lateral pipes

8. These preferably extend from a vertical manifold pipe 9, the vertical pipe being connected with a horizontal pipe 9^a and this

50 leads to an exhaust fan 9^b. The pipes 8 are preferably tapered and have tapered

openings 11 leading from tapered channels

10. The effect of thus tapering the pipes, openings and channels is to cause a uniform

55 flow of air throughout the length of the

drying chamber and throughout the height of the drying chamber. The air passes horizontally across the drying chamber from the heating chamber and the flow of air is induced by exhausting the air by means of 60 the fan 9^b. In general this mode of directing the air currents through the drying chamber is shown and described in my patent dated Jan. 26th, 1915 #1,126,567. Tracks 12, 13 and 14 extend lengthwise 65 through the drying chamber. A run-way 15 is provided between the tracks 12 and 13 and a run-way 16 between the heating chamber 5 and the track 14. Cars 17 are arranged on these tracks, these cars carrying the racks 70 18. Trays 19 are mounted in these racks. The trays 19 are inclined in the direction of the flow of the air and are provided with perforated bottoms, preferably wire mesh bottoms, so that the air having the general 75 horizontal direction through the drying chamber reaches all parts of the fruit, some of the air passing through the wire bottoms. This feature is of great importance in giving to the vapor-laden air free movement 80 and effects a rapid evaporation and prevents the formation of dead pockets in which there is not only a lack of drying but may be actual condensation and resulting imperfect product.

85 Cars are delivered through the door 20 on the track 12 to the air lock 3. From this they are passed through the door 21 to the drying chamber 2. They are taken from the drying chamber past the door 22 into the air lock 4. A pit 23 is arranged crosswise 90 of the house in the air lock 4 and this is provided with a track 23^a. A car 24 is arranged on the track 23^a and carries a turn table 24^a. A track 25 is arranged on the turn table 24^a and the car as it comes from the track 12 is passed on to the track 25 on the turn table. The car 24 is then moved along the track 23^a bringing the track 25 opposite the track 13. The door 26 is then 95 opened and the car is again moved into the drying chamber on the track 13. After advancing through the drying chamber on the track 13 it is removed by way of the door 27 to the air lock 3. A circular pit 28 is 100 arranged in the air lock 3 and in this pit a turn table 29 is mounted. Two tracks 30 are arranged on the turn table 29 and these tracks are so spaced as to register with the 105 tracks 13 and 14. A car passing through 110

the door 27 passes on to the track 30. The turn table is then rotated one-half a turn. This carries the track 30 on which the car is then mounted into register with the 5 track 14 and the companion track 30 into register with the track 13. The car is then moved through the door 31 back into the drying chamber 2 and thence through this chamber and discharged through the door 10 32 onto the track 25, the car 24 having been moved so as to bring the track 25 into register with the track 14. The turn table 24^a is then swung bringing the track across the house and lengthwise of the air lock 4. The 15 car is discharged by way of a track 33 and door 34.

In the ordinary operation of the device, assuming that the drying house is filled, a car is taken through the door 32 and 20 charged. The cars on the track 14 are then advanced thus leaving a space next the door 31. The car is then taken from the track 13 and by way of the turn table 29 reversed and transferred to the space next to the 25 door 31, thus filling the track 14. The cars on the track 13 are then advanced forming a space opposite the door 26. This space is then filled by transferring a car through the door 22 from the track 12. The cars 30 on the track 12 are then advanced and a fresh car is introduced through the door 20.

It will be observed that the trays 19 are not only inclined in the direction of the air but that the inclinations of the trays on the 35 tracks 13 and 14 are reversed so that the trays are, as arranged through the drier, so inclined as to have the air pass downwardly through them and also upwardly through them and the air is delivered to 40 them from opposite ends, thus preventing any undesirable air pockets. It will further be observed that while the advantage of passing the air crosswise through the drying chamber is obtained thus assuring a 45 more certain distribution of the air, at the same time, the fruit is advanced toward the incoming air, the trays on the track 14 being subjected to the drying effect of the air before it is moisture-laden from the 50 evaporation, the trays on the track 13 being partially dried being subjected to the partially laden air and the cars on the track 12 being fresh are subjected to the air carrying the moisture from the tracks 14 55 and 13. In this way the full evaporating effect of the air is obtained and the greater efficiency of the added tracks is had without decreasing the drying effect that is obtained on the track subjected to the incoming air.

The alternate arrangement of the inclination of the material being dried not only assures the movement of the air through the perforated trays from top to bottom 60 and from bottom to top, but also prevents

any decided inclination of the air away from the horizontal and what tendency there is to deflect gives more pronounced impact of the air upon the fruit or material being dried, so that a greater efficiency 70 results. The reversing of the direction in which the air strikes the material is also of considerable importance, because the initial impact of the air with one inclination is on the top, and with the other inclination 75 at the bottom.

What I claim as new is:—

1. In a drier, the combination of a drying chamber; means for forcing a current of air horizontally through said chamber; 80 and drying trays in said chamber, said trays having perforated bottoms and being inclined to the horizontal and to the direction of the flow of air.

2. In a drier, the combination of an elongated drying chamber; means for forcing a current of air horizontally across said chamber; and drying trays in said chamber, said trays having perforated bottoms and being inclined to the horizontal and to the 90 direction of the flow of air.

3. In a drier, the combination of a drying chamber; means for forcing a current of air horizontally through said chamber; and two tiers of trays placed successively 95 in the direction of the flow of air, both tiers having their trays inclined to the direction of the flow of air and the inclination in one tier being reversed from that of the other.

4. In a drier the combination of a drying 100 chamber; means for forcing a current of air horizontally through said chamber; and drying trays in stacks in spaced and open relation in said chamber, said trays having perforated bottoms and being inclined to the 105 horizontal and to the direction of the flow of air.

5. In a drier, the combination of a drying chamber; means for forcing a current of air horizontally through said chamber; and 110 two tiers of trays placed successively in the direction of the flow of air, both tiers having their trays inclined to the direction of the flow of air and the inclination in one tier being reversed from that of the other, 115 the bottoms of said trays being perforated.

6. In a drier, the combination of a drying chamber having a plurality of tracks therein; cars on said tracks having tray racks thereon; means for forcing air through the chamber crosswise of the tracks; and inclosed ways for transferring said cars from a track 120 more remote from the incoming air to a track nearer the incoming air.

7. In a drier, the combination of a drying 125 chamber; rows of tray racks in said chamber; means for forcing air through the chamber crosswise of the rows, the trays on said racks being inclined in the direction of the flow of air, said trays having 130

perforated bottoms; and inclosed ways for advancing the rows of racks and for transferring the racks from a row more remote from the incoming air to a row nearer said incoming air.

8. In a drier, the combination of a drying chamber; rows of tray racks in said chamber; means for forcing air through the chamber crosswise of the rows; trays on said racks, said trays being inclined to the direction of the flow of air and the trays in succession in the flow of air having their inclinations reversed; and inclosed ways for advancing the rows of racks and for transferring the racks from a row more remote from the incoming air to a row nearer said incoming air.

9. In a drier, the combination of a drying chamber; rows of tray racks in said chamber; means for forcing air through the chamber crosswise of the rows; trays having perforated bottoms, on said racks, said trays being inclined to the direction of the flow of air and the trays in succession in the flow of air having their inclinations reversed; and inclosed ways for advancing the rows of racks and for transferring the racks from a row more remote from the incoming air to a now nearer said incoming air.

10. In a drier, the combination of a drying chamber; rows of tray racks in said chamber; means for forcing air through the chamber crosswise of the rows; trays on said racks, said trays being inclined in the direction of the air; and inclosed ways for advancing the rows of racks and for transferring the racks from a row more remote from the incoming air to a row nearer said incoming air and for reversing the inclination of the trays as the racks are transferred.

11. In a drier, the combination of a drying chamber; means for directing a flow of air crosswise of the chamber; and inclosed ways for advancing material to be dried lengthwise of the chamber and for transferring the material from a path more remote from the incoming air to a path less remote from the incoming air.

12. In a drier, the combination of a drying chamber; means for directing a flow of air crosswise of the chamber; a series of paths along which the material is advanced lengthwise of the chamber; and means for changing the relation between material while inclosed and its path and the inflow of air to the chamber.

13. In a drier the combination of a drying chamber; means for forcing a current of air horizontally through said chamber; drying trays in said chamber, said trays having perforated bottoms and being inclined to the direction of the flow of air, and means for reversing the relation between the direction of the flow of air and the inclined trays,

whereby the air in one relation passes through the tray from top to bottom and the other relation through the tray from bottom to top.

14. In a drier the combination of a drying chamber; means for forcing a current of air horizontally through said chamber; drying trays in stacks in spaced and open relation in said chambers, said trays having perforated bottoms and being inclined to the direction of the flow of air; and means for reversing the relation between the direction of the flow of air and the inclined trays whereby the air in one relation passes through the trays from top to bottom and the other relation through the trays from bottom to top.

15. In a drier the combination of a drying chamber; means for forcing a current of air horizontally through said chamber; two tiers of trays placed successively in the direction of the flow of air, both tiers having its trays inclined to the direction of the flow of air, said trays having perforated bottoms; means for reversing the relation between the direction of the flow of air and the trays in each tier, whereby the air in one relation passes through the tray from top to bottom and the other relation through the tray from bottom to top.

16. In a drier the combination of a drying chamber; means for forcing a current of air horizontally through said chamber; and two tiers of trays placed successively in the direction of the flow of air, both tiers having the trays inclined to the horizontal and to the direction of the flow of air, said trays having perforated bottoms.

17. In a drier the combination of an elongated drying chamber; means for forcing a current of air horizontally across said chamber; two tiers of drying trays placed successively across said chamber, each tier extending the full length of said chamber, the trays of each tier being inclined to the horizontal and to the direction of the flow of air, said trays having perforated bottoms.

18. In a drier the combination of an elongated drying chamber; means for forcing a current of air horizontally across said chamber; two tiers of drying trays placed successively across said chamber, each tier extending the full length of said chamber, the trays of each tier being inclined to the direction of the flow of air and having perforated bottoms; and means for reversing the relation between the direction of the flow of air and the trays, whereby the air in one relation passes through the trays from top to bottom and the other relation through the trays from bottom to top.

19. In a drier the combination of a drying chamber; rows of tray racks in said chamber; means for forcing air through the chamber crosswise of the rows and across a

plurality of rows; trays on said racks, said trays being inclined to the direction of the flow of air and having perforated bottoms; means for advancing the rows of racks and 5 for reversing the relation between the direction of the flow of the air and the inclination of the trays.

20. In a drier the combination of a drying chamber; rows of tray racks in said 10 chamber; means for forcing air through the chamber crosswise of the rows and across a plurality of rows; trays on said racks, said trays being inclined to the direction of the air and having perforated bottoms; means 15 for advancing the rows and for reversing the racks to reverse the relation between the direction of the flow of the air and the trays, whereby the air in one relation passes through the trays from top to bottom, and 20 the other relation through the trays from bottom to top.

21. In a drier the combination of an elongated drying chamber; means for forcing a current of air horizontally through said 25 chamber; devices for supporting the material to be dried in a plane inclined to the direction of the flow of air; and means for reversing the relation between the direction of the flow of air and the material.

30 22. In a drier the combination of a drying chamber; means for forcing a current of air horizontally through said chamber; devices for supporting the material at an inclination to the direction of the flow of air; 35 means for reversing said devices to reverse the inclination to the direction of the flow of air.

23. In a drier the combination of a drying chamber; means for forcing a current 40 of air horizontally through said chamber; and a plurality of tiers of supports for material to be dried, said supports holding the material at an inclination to the direction of the flow of air and giving to the material 45 in one tier of supports an inclination in a reverse direction from the inclination of the material in another tier.

24. In a drier the combination of a drying chamber; means for forcing a current of air 50 horizontally through said chamber; a plurality of tiers of supports for material to be dried, said supports holding the material at an inclination to the direction of the flow of air and giving to the material in one tier 55 of supports an inclination in a reverse direction from the inclination of the material in another tier; and means for reversing the relation between the direction of the flow of air and the material on each tier 60 of supports.

25. In a drier the combination of a drying chamber; means for forcing a current of air horizontally through said chamber; a plurality of tiers of supports for material 65 to be dried, said supports holding the ma-

terial at an inclination to the direction of the flow of air and giving to the material in one tier of supports an inclination in a reverse direction from the inclination of the material in another tier; and means for 70 reversing each tier of supports to reverse the inclination of the material to the direction of the flow of air.

26. In a drier the combination of an elongated drying chamber; means for forcing a 75 current of air horizontally across said chamber; a plurality of tiers of supports for material to be dried, said supports holding the material at an inclination to the direction of the flow of air; means for reversing the 80 relation between the direction of the flow of air and the inclination of material.

27. In a drier the combination of an elongated drying chamber; means for forcing a current of air horizontally across said 85 chamber; and a plurality of tiers of supports for material to be dried, said supports holding the material at an inclination to the direction of the flow of air, the inclination of the material in one tier of 90 supports being in reverse relation to that of the material on another tier of supports.

28. In a drier the combination of an elongated drying chamber; means for forcing a current of air horizontally across said 95 chamber; a plurality of tiers of supports for material to be dried, said supports holding the material at an inclination to the direction of the flow of air, the inclination of the material in one tier of supports being in 100 reverse relation to that of the material on another tier of supports; and means for reversing the relation between the direction of the flow of air and the inclination of material in each tier of supports. 105

29. In a drier the combination of a drying chamber, having a plurality of tracks therein; cars on said tracks having material supports thereon, said supports being adapted to hold said material at an inclination; means for forcing a current of air through said chamber horizontally crosswise of said tracks; and means for transferring the cars from the track more remote from the incoming air to a track 110 nearer the incoming air.

30. In a drier the combination of a drying chamber, having a plurality of tracks therein, cars on said tracks having material supports thereon, said supports being 115 adapted to hold said material at an inclination, means for forcing a current of air through said chamber horizontally crosswise of said tracks; and means for transferring the cars from the track more remote 120 from the incoming air to a track nearer the incoming air, and for reversing the relation between the direction of the flow of air and the inclination of material.

31. In the method of drying materials, 130

which consists in arranging material on a plurality of rows of supporting means, advancing the supporting means with the material thereon lengthwise of said rows, subjecting the material to a flow of air directed crosswise of the direction in which the rows are advanced and varying the relation between the flow of air and the material, whereby the material is initially remote from the incoming air and later brought nearer the incoming air.

32. The method of drying material which consists in arranging the material on a plurality of rows of supporting means, subjecting the material to a flow of air directed crosswise of the rows, advancing the material lengthwise of a row remote from the incoming air, transferring it to and advancing it along a row nearer the incoming air.

33. The method of drying material, which consists in arranging material on a plurality of rows of supports, advancing the material on said supports lengthwise of said rows, subjecting the material to a flow of air directed crosswise of the rows and with

the direction of the flow of air and the supports inclined relatively to each other, and varying the relation between the flow of air and the material whereby the inclination is reversed.

34. The method of drying material, which consists in arranging material on a plurality of rows of supports, advancing the material on said supports lengthwise of said rows, subjecting the material to a flow of air directed crosswise of the rows and with the direction of the flow of air and the supports inclined relatively to each other, and varying the relation between the flow of air and the material whereby the inclination is reversed and the material is initially remote from the incoming air and later brought nearer the incoming air.

In testimony whereof I have hereunto set my hand in the presence of two subscribers.
